US00D992768S

(12) **United States Design Patent** (10) **Patent No.:** **US D992,768 S**
Zhou (45) **Date of Patent:** **** Jul. 18, 2023**

(54) **CANDLESTICK**

(71) Applicant: **SHENZHEN HUARONG PENGHUI TECHNOLOGY CO., LTD**, Shenzhen (CN)

(72) Inventor: **Zepeng Zhou**, Shenzhen (CN)

(73) Assignee: **SHENZHEN HUARONG PENGHUI TECHNOLOGY CO., LTD.**, Shenzhen (CN)

(**) Term: **15 Years**

(21) Appl. No.: **29/813,332**

(22) Filed: **Oct. 28, 2021**

(51) LOC (14) Cl. **26-01**

(52) U.S. Cl.

USPC **D26/9**

(58) **Field of Classification Search**

USPC D26/6-16, 20-23; D11/121, 130, 131, D11/131.1, 143

CPC F21V 35/00; F21V 35/003; F21V 35/006; F21S 6/001; F21S 10/04; C11C 5/00; C11C 5/008

See application file for complete search history.
